ABSTRACT: A catapult or slingshot has a handle with a chamber formed therein. A propulsion member is movably disposed in the chamber and extends outwardly thereof for connection with elastic strand members, and the propulsion member has an associated spring means within the chamber to effect movement of the propulsion member in coordination with release of the strand from an extended position.

CATAPULT

BACKGROUND OF THE INVENTION:

1. Field of the Invention:

This invention pertains to new and novel slingshot or catapult devices adapted to project arrows, spherical objects, and the like against targets or game.

2. Statement of the Prior Art:

Variations on the conventional slingshot which consists of two arms having an elastic connected to each include proposals to incorporate springs in the arm structure (Jones, Patent No. 1,346,745 of July 13, 1920), and reciprocating pistons mounted within slingshot handles (Beatty, Patent No. 1,153,415 of September 14, 1915). These prior proposals, while probably increasing to some extent the effectiveness of accuracy and force of propulsion of the devices, have however either been too cumbersome or costly for general acceptance. These prior devices moreover do not center the propulsive thrust in a line of intended sight.

SUMMARY OF THE INVENTION:

The present invention provides catapult devices wherein thrust force of resilient strands is coordinated to perform either simultaneously or in close sequence with associated spring means. A related objective of the invention concerns the centering of thrust forces in a linear direction whereby the efficiency of the propulsive energy is substantially enhanced. The structural principles embodied in this device include the elimination of fastening means for strands as often encountered in devices of this nature which unduly encumber the apparatus and cause deviation of thrust.

It is contemplated that the apparatus hereof will be useful in the propulsion of articles or projectiles of various types, such as elongated arrows or spherical objects, and that these may be alternatively projected from the apparatus without any substantial modification thereof.

Another advantage introduced by the linear force principle of this invention is that of accuracy of aim. The present invention avoids the deviation of course of propelled objects occasioned by non-balanced application of forces experienced where widely separated arms or bows are employed thus causing an unbalanced tension on either side thereof.

Other and further objects and advantages of the invention will become apparent to those skilled in the art from a consideration of the following specification when read in conjunction with the annexed drawings.

BRIEF DESCRIPTION OF THE DRAWINGS:

FIGURE 1 is a perspective view of a first form of catapult device constructed and assembled in accordance with the teachings of this invention;

FIGURE 2 is an enlarged elevational view, partially broken away for disclosure of details, of the device of **FIGURE 1**;

FIGURE 3 is a vertical cross-sectional view taken on the line 3-3 of **FIGURE 2**, looking in the direction of the arrows;

FIGURE 4 is a perspective view of a modified form of the device;

FIGURE 5 is a top plan view of the form of the invention shown in **FIGURE 4**;

FIGURE 6 is a perspective view of a further modified form of the invention;

FIGURE 7 is an enlarged cross-sectional view on the line 7-7 of **FIGURE 6**, looking in the direction of the arrows, showing first and second operating positions of the components in full and phantom lines;

FIGURE 8 is another vertical cross-section; and

FIGURE 9 is a sectional view on line 9-9 of **FIGURE 8**, looking in the direction of the arrows.

DESCRIPTION OF THE PREFERRED EMBODIMENTS:

Reference is made initially to **FIGURES 1** through 3 of the drawings wherein the first form of catapult device hereof is

generally identified by reference numeral 10. The device 10 comprises a body portion 12 formed of wood, plastic, or other suitable, rigid material, and having a top 14 and a bottom 16. The body portion further has a leading side 18 and a trailing side 20, these sides being contoured in such manner that the device may be comfortably and efficiently gripped in the hand of the user as shown in **FIGURE 1**. The top 14 of the body portion is forwardly extended in the direction of the leading edge 18, forming a ledge section 22.

Formed in the body portion 12 and opening on the top 14 thereof is an elongated, vertically extending chamber 24 of generally square cross-sectional form. The chamber is defined by bottom 26 and forward end rear walls 28, 30.

A propulsion member 32 is movably mounted within the chamber and is of metal or equivalent material. The member 32 comprises a lever having an inner section 34 and an integral, outer section 36, the major portions of which are of generally square cross-section. The inner section 34 is mounted pivotally on a cross pin 38 extended transversely of the body portion, across the chamber, and the inner section has rear faces 40 and 42 angularly related to one another, and forward faces 44 and 46 also angularly related. The face 46 is stepped at 48 to form an indented lip 50. A leaf spring 52 comprising a first arm 54, bend portion 56, and an elongated second arm 58 is disposed in the chamber with the first arm 54 bearing flush against the forward wall 28 thereof and the bend portion 56 resting on the bottom 26. The second arm 58 engages the lip 50 of the lever forward face 46, and normally urges the lever to the position shown in phantom lines in **FIGURE 2** wherein the face 42 bears against the wall 30 and the face 44 abuts the wall 28.

The lever outer section 36 has a top portion with a strand engaging loop 60 having an entry portion 62. The loop 60 comprises, as best shown in **FIGURE 3**, an extension of the lever, and is co-equal in width therewith. An elongated cord or band means 64 having flexible strands 66, 68 connected at a forward portion 70 and at a pocket section 72 is extended through the loop 60 at the portion 70. The cord is of an elastic material, such as rubber, and the pocket means 72 has grasping means 76 on each of its sides and an area 78 shaped to receive a missile to be propelled, such as a ball.

In **FIGURES 4** and 5, a first modified form of the invention, designated 10a is shown. In this instance, the propulsion member 32a is modified for use with an elongated projectile, such as an arrow 100, with a cylindrical shaft 102. The outer section 36a has a half round groove 104 centered on its distal extremity, and has loop elements 106, 108 extended from the lateral sides thereof. The loop elements have vertical openings therein, with side entry slots 110, 112, respectively. The cord or band means 64a comprises two separate, endless straps 114 and 116, engaged in the loops 106 and 108. A pocket assembly 72a has leading portions 118, 120, and these are engaged with the respective strands. Side panels of the pocket assembly have openings 122, 124 for grasping the arrow shaft 102.

In operation, these forms of the invention involve an initial grasping of a missile or arrow in the pocket sections 72 or 72a. As the cord means 64 is extended, the propulsion members 32 or 32a is tilted to the upright position against the pressure of the spring means to a position wherein it reaches a limit in which the rear face 40 or 40a of the lever contacts the wall 30 or 30a of the chamber. The cord may be stretched to a limit position, one example of which would be approximately to an extent equal to three times the unextended length thereof. Upon release of the cord pocket, the cord means contracts and the spring means forces the lever sharply forward to the phantom line position of **FIGURE 2**, wherein it rests upon the ledge of the top side 14 of the body portion. The line of thrust is of course controlled by aiming of the device, and the projectile is cast forwardly along this line of thrust.

FIGURES 6 through 9 show a second form of the invention, designated 10b. There, a body portion 12b is formed of wood or the like and has a top 14b and bottom 16b. The body por-

tion, for reference purposes, has leading and trailing sides 18b, 20b of curvilinear form.

An elongated chamber 24b of circular section extends fully through the body portion from top to bottom, being open at the top and being closed at the bottom by a plug member 200. Reciprocally mounted in the chamber is a propulsion member 32b of cylindrical form having an outer section 36b and an inner section 34b, the latter having an elongated, vertical slot 202 therein with a cross pin 38b of the body portion projecting therethrough. The propulsion member has a lower end 204 with a connection eye 206 therein. A coil spring 52b is extended between the eye 206 and a similar eye 208 anchored on the plug 200.

The outer end of the propulsion member has a groove 104b therein to slidably support an arrow shaft or the like. Immediately below the groove, a transverse opening 210 is formed in the propulsion member, and an entry slot 212 which receives cord means 64b extends into the opening. The cord means has a pocket (not shown) at a remote location.

In operation, the second form of the invention 10b again involves an initial stretching of its cord means 64b, and in this case, the body portion 12b is tilted rearwardly during the aiming process as is shown in FIGURE 7. The extension of the cord means also withdraws the propulsion member to the limit of its outward withdrawal wherein the cross pin 38b contacts the base of the slot 202. Upon release, the spring contracts along with the contraction of the elastic cord 64b, again resulting in a coordinated propulsive force on the missile or projectile.

Having described and illustrated two embodiments of this invention in some detail, it will be understood that these descriptions and illustrations have been offered by way of example, and that the invention is to be limited in scope only by the appended claims.

I claim:

1. In a catapult device for propulsion of an object:
  - a handle comprising a body portion with a top and a bottom;
  - the body portion having a chamber formed therein opening on the top thereof;
  - a propulsion member mounted movably in the chamber and extending outwardly thereof;
  - spring means in the chamber urging the propulsion

member to a first, non-operating position; resilient strand means secured to the propulsion member on the exterior of the body portion, the strand means being engageable with the object to be propelled at a location remote from the connection of the strand means with the propulsion member; whereby

the strand means may be extended in opposition to the spring bias which is urging the propulsion member to said non-operating position and, upon release, the propulsion member returns to the first non-operating position thereby aiding in propulsion of the object from the catapult.

2. The invention of Claim 1, wherein:

the propulsion member comprises an elongated element disposed in the chamber for limited sliding movement; the elongated element having a slot therein; a cross pin secured to the body portion and extending across the chamber through the slot; a coil spring within the chamber secured at one end to the body portion adjacent the bottom thereof and at the other end to the elongated element; and the movement of the propulsion member being effected by extension of the spring to the extent of travel of the member with respect to the cross pin.

3. The invention of Claim 2, wherein:

the propulsion member includes an upper end; and the upper end has a groove formed therein to effect directional control of the object to be propelled.

4. The invention of Claim 1, wherein:

the strand means has a pocket section for grasping the object to be propelled.

5. The invention of Claim 1, wherein:

the propulsion member includes an inner lever and an outer lever, the inner lever being pivotally mounted within the chamber; and the spring means including a leaf section engaged by the inner lever.

6. The invention of Claim 5, wherein:

the body portion includes a leading side having a horizontal ledge; and the outer lever has a leading portion which abuts the ledge and which serves as a stop means therefor.
